Primary Examiner — Melanie Pellegrini*(74) Attorney, Agent, or Firm* — Clements Bernard Baratta; Lawrence A. Baratta, Jr.(57) **CLAIM**

The ornamental design for a ring, as shown and described.

DESCRIPTION

FIG. 1 is a top perspective view of a ring in an engaged configuration;

FIG. 2 is a bottom perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a front perspective view of the ring in a disengaged configuration; and,

FIG. 10 is a rear perspective view thereof.

The broken lines shown in the drawings represent portions of the ring which form no part of the claimed design.
